VERMICULITE PROCESSING MACHINE

William H. D. Hinchman, Detroit, Mich., assignor
to The Zonolite Company of Montana, Detroit,
Mich., a corporation of Montana

Application March 2, 1938, Serial No. 193,563

3 Claims. (Cl. 209—29)

This invention relates to a vermiculite processing machine.

This invention is particularly concerned with an apparatus for expanding or exfoliating fragments of vermiculite, for separating the stones from the exfoliated vermiculite, for separating the smaller fragments of exfoliated vermiculite from the larger, and for classifying according to size these fragments of exfoliated vermiculite. It is old in the art to crush vermiculite into fragments of whatever commercial size desired and thereafter heating these fragments to the proper temperature to expand or exfoliate them. Exfoliated vermiculite is relatively fragile. If the expanded vermiculite is not handled carefully, the fragments are broken or comminuted into smaller fragments and dust which, in some instances, are commercially less desirable.

It is an object of this invention to produce a simple, economical, and efficient apparatus and method for separating the dust and stones from the fragments of exfoliated vermiculite with practically no breaking or comminuting of the same. This object has been achieved generally by passing the exfoliated vermiculite fragmentary material as it comes from the expander across an air stream which carries away the smaller fragments and the dust, diverts the fragments of vermiculite from the direction in which they were traveling prior to passing into the air stream thereby causing the heavier fragments of foreign material, such as stones and the crude or non-exfoliated vermiculite, to continue in substantially the same direction as when they entered the air stream and thereby separate from the exfoliated fragments of vermiculite.

In the drawings:

Fig. 1 is an elevation partly in section showing the complete expanding, conveying, and separating apparatus.

Fig. 2 is a detail elevation partly in section of the apparatus for pneumatically separating the dust and foreign material, such as stones or crude vermiculite ore, from the exfoliated vermiculite fragments.

Fig. 3 is a vertical section through the expander and elevating conveyer for the expanded vermiculite.

Fig. 4 is a detail sectional view through the blower pipe and the dust and stone eliminator showing the gate valve and hurdle over which the exfoliated vermiculite travels.

Figs. 5, 6, 7 and 8 are sectional views respectively along the lines 5—5, 6—6, 7—7 and 8—8 of Fig. 2.

Exfoliated vermiculite is used in various well-known sizes generally varying in size from such that will pass through a half inch mesh downwardly to dust. The crude vermiculite ore is first crushed or ground to fragments of whatever size desired (for example, fragments sufficiently small to pass through a quarter inch mesh) and then this crude ore is heated to exfoliate the same.

Referring to Figs. 1 and 2, there is shown a device for expanding the fragments of crude exfoliated vermiculite. The crude crushed ore is dumped into a hopper 1 from which it is fed by means of a screw 2 to a mechanical elevator 3.

The mechanical elevator 3 is preferably of the bucket elevator type. The elevator 3 dumps the crude ore to the inclined chute 4 down which the ore passes and is discharged into a stack 5. The stack 5 is provided with a plurality of downwardly inclined baffles 6 positioned one above the other from the top to the bottom of the stack 5. The stack 5 is provided with a lining 7 of any suitable refractory brick. The stack is provided with an opening 8 in the wall thereof in which is seated the burner block 9. The burner block 9 is provided with an opening 10 through which is passed the fuel outlet nozzle of any suitable type of fuel oil burner diagrammatically shown at 11.

The oil burner is provided with a blower 12 for supplying air under pressure to the nozzle of the burner. As the crushed vermiculite crude ore passes in a zigzag path from one baffle 6 on to the next baffle beneath it, the crude vermiculite fragments are heated by the burner to the temperature required to properly exfoliate or expand the same. The exhaust gases from the furnace pass upwardly through the pipe 13 into the enlarged chamber 14 where the speed of the air current is materially diminished thereby permitting any exfoliated vermiculite which is carried upwardly through the pipe to separate from the exhaust gases and fall down the discharge pipe 15 on to the feeder chute 16 leading from the bottom of the stack 5 to the chain and bucket elevator generally designated 17. The exhaust gases from the furnace then pass upwardly out of the cyclone chamber or collector 14 through the stack 18 to atmosphere.

When the vermiculite fragments reach the bottom of the stack 5 substantially all of the ore has been expanded. However, there is still some crude unexpanded or incompletely expanded vermiculite, the amount depending upon the efficiency of the expanding furnace. Then, too, there are also stones and other non-expandable foreign material mixed with the vermiculite which

must be separated. The expanded vermiculite, including the foreign material, passes down the chute 16 where it is picked up by the chain and bucket elevator 17, elevated vertically, and then 5 delivered into the chute 18 which is preferably in the form of a sheet metal pipe. The bucket conveyer 17 is enclosed within the closed housing 19 which is provided with an opening through which the expanded vermiculite flows from the 10 chute 16 into the conveyer buckets 20. The housing 19 also communicates with the chute 18 and the pipe 21 which leads from the upper end of the housing 19 into the enlarged cyclone type of expansion chamber 22 which is similar in construction 15 to the cyclone chamber 14.

The expanded vermiculite can be propelled through the chute 18 in any suitable manner. However, bearing in mind that the exfoliated vermiculite is fragile and that it is desirable to subject it to as little comminuting, breaking or 20 grinding action as possible, therefore the means for propelling the expanded vermiculite along the chute 18 should do so gently. A simple, economical and gentle manner for propelling the 25 exfoliated vermiculite along chute 18 is by gravity. To this end the chute 18 is inclined downwardly from the housing 19 to the classifier 23. The inclination of the chute 18 can be varied within wide limits, but preferably the inclination should 30 be no greater than is necessary to cause the expanded vermiculite to jump over the hurdle 24, as described below, because, as above explained, the exfoliated vermiculite should not be subjected to any harsher or rougher handling than 35 is necessary to preserve its original expanded size.

Referring to Fig. 2, the pipe 18 leads downwardly where it is joined to and communicates with the classifier 23. The pipe 18 is provided 40 with an elongated opening 25 preferably in its upper wall. An enlarged housing 26 is mounted upon and fixed to the pipe 18 over the opening 25. This housing 26 cooperates with this portion of the pipe 18 to form an enlarged chamber 28 45 which acts as an eliminator of the dust and stones from the expanded vermiculite. The housing 26 is provided with a fine wire mesh 27 which separates the lower portion of the chamber 28 from the upper portion of the chamber.

50 The wire mesh 27 is preferably sufficiently fine to permit the exfoliated vermiculite dust to pass through the same. However, the mesh of the screen 27 will be determined largely by the size of the largest dust or fine fragments of exfoliated 55 vermiculite that one desires to eliminate or separate from the main body of the expanded vermiculite.

The bottom wall of the pipe 18 is provided with 60 an opening 29 which is controlled by a sliding gate valve 30 secured to the bottom of the pipe 18 by a wing nut 31 and bolt 32 which slidably engages the slit in the elongated slot 33. Thus, by adjusting the slide 30 the opening 29 can be 65 completely closed or opened to whatever extent desired depending upon the several variable factors, such as the speed at which the exfoliated vermiculite 34 is traveling, the speed of the air current flowing upwardly within pipe 35 and through opening 29 into the pipe 18 and housing 70 26, the height of the hurdle 24, and other variable factors.

A hurdle in the form of a plate 24 is slidably secured on the pipe 18 by the wing nut 36 and bolt 37 which engages the slide 24 in the elongated slot 38. The pipe 18 is rectangular in

cross section, as shown in Figs. 5 and 7. The hurdle 24 is rectangular in cross section and projects upwardly through the bottom wall 40 of the pipe 18 into the pipe 18 and extends from one side wall 39 to the other of the pipe 18, see Fig. 8. 5 The height of the hurdle 24, that is, the distance the hurdle 24 extends from the bottom wall 40 of the pipe 18 upwardly will be varied to suit the numerous variable factors or conditions above mentioned and also will depend upon the kind 10 and the size of the material being separated. The pipe 35 extends vertically downwardly, as shown in Figs. 1 and 2, where it serves as a discharge chute for dust and other foreign material 15 from the expanding vermiculite.

The side wall of the tube is provided with an opening 41 which serves as an outlet for a pipe 42 which leads from, and communicates with, a pipe 43 connected to the high pressure or discharge outlet of the blower fan 44. The suction 20 or low pressure side of the fan 44 is connected by pipe line 45 with an enlarged housing 22 which forms a cyclone dust collector. The interior of the housing 22 is connected with the classifier 23 by the pipe line 47. The housing 22 25 is connected with the upper end of the housing 19 by the pipe line 21. The pipe line 21 is connected with the upper end of the housing 26 by the pipe line 46. Thus, as shown by the arrows in Fig. 2, pipe 46, pipe 21, housing 22, and 30 pipe 45 connect the dust eliminating housing 26 with the suction side of the fan 44 and pipes 43, 42 and 35 connect the housing 26 with the high pressure or outlet side of the blower fan 44. Pipe line 43 leads to a dust sack 48. 35

The chamber 26 is provided with an incandescent lamp 50 and an observation window 51. The operator uses the observation window 51 to determine what has taken place within the chamber 28 and accordingly adjusts the valve 30 to 40 vary the size of the opening 29 to control the velocity and volume of air passing therethrough and adjust the hurdle 24 to the height required to properly separate the stones and dust from the exfoliated vermiculite. 45

In operation the exfoliated vermiculite 34 slides downwardly along the bottom wall 40 of the pipe 18. Preferably the hurdle 24 projects upwardly from the bottom 40 into the pipe 18 a sufficient distance such that the distance between the top edge 55 and a line dropped perpendicularly therefrom to the bottom wall 40 of the pipe 18 is approximately the same length as the depth of the exfoliated vermiculite flowing down the pipe 18. As the exfoliated vermiculite 55 reaches the opening 29, the upward blast of air elevates the exfoliated vermiculite fragments which are relatively light compared to any stones and crude vermiculite that is present in the stream of material flowing down the chute 18. 60 Thus, as the exfoliated vermiculite reaches the opening 29 it is elevated out of its normal course parallel to the bottom 40 of the chute 18 and diverted or caused to jump the hurdle 24 where it passes out of the air stream and falls downwardly 65 to the bottom 40 of the pipe 18 beyond opening 29 and again resumes its downward course and finally passes into the classifier 23. The classifier 23 may be a conventional grain classifier which classifies the expanded vermiculite fragments according to size. 70

Since the stones and crude ore are heavier than the expanded vermiculite, this foreign material is not elevated by the upward blast of air, but strikes the hurdle 24 and falls downwardly through 75

the opening 29 into the waste material discharge chute 35. The upward blast of air passing through the opening 29 carries all of the dust and the lighter fragments of exfoliated vermiculite upwardly in the chamber 28. The dust and those fragments sufficiently fine to pass through the mesh 27 are carried by the air current upwardly through the pipe line 46 into the pipe 24 and dust collector 22 where the dust, due to the decreased 10 velocity of the air, separates from the air and is collected in the collector 22 from which it can be removed through a door in the bottom of the collector 22 or in any other suitable manner.

The classified expanded vermiculite is discharged 15 from the classifier 23 through lines 60 and 61 into the storage bins 62.

Although the apparatus and method hereinabove described is for separating dust, stones and other undesirable material from exfoliated vermiculite, it is understood that this apparatus and method can be used for separating dust, stones, 20 nails and other undesirable materials from other fragmentary material similar in nature to exfoliated vermiculite, such as asbestos, wheat, oats 25 and other grains, feathers, cereals, granular cork. In cleaning grains the dust would be collected as hereinabove described, the chaff would follow the path of the exfoliated vermiculite and the grain, which is the heavier material, would fall 30 down the chute 35.

The size of the opening 29 and the height of the baffle 24 will be determined by the weight of the material that is being passed through the separator, the velocity of the upwardly flowing air stream and the other variable factors above-mentioned. The point is that this apparatus can be used for separating fragmentary or granular materials having different weights for like volumes.

42 The system is adjusted so that more air is taken out of housing 26 through pipe 46 than is put into housing 26 through pipes 42 and 35. Therefore, more air is taken in to housing 26 through pipe 18. This prevents dust from blowing 45 out of the machine into the plant in which it is installed.

The suction in pipe 46 is necessary as well as the pressure in pipe 42. The pressure head in lines 43, 42 and 35 is constant because the blower 50 runs at constant speed. Thus, as the valve 30 is moved towards closed position to decrease the size of the outlet 29 from line 35 the speed as well as the force of the air blast is increased thus hoisting the vermiculite higher over the baffle 24.

55 I claim:

1. A machine for separating fragments of exfoliated vermiculite from debris such as stones and unexfoliated fragments of vermiculite, comprising an inclined runway along which the exfoliated vermiculite and debris moves by gravitation, a closed circuit for effecting a flow of air across the said runway comprising blower means and pipe lines connected to the inlet and outlet sides of the blower means, an enlarged chamber 60 connected below the runway to the pressure air line and above the runway to the suction air line for slowing down the velocity of the air forced into the enlarged chamber by the pressure air line, the pressure pipe line being operatively connected with the runway to produce an upward 65 blast of air across the line of travel of said exfoliated vermiculite and debris and the suction air line being positioned above the runway whereby as the exfoliated fragments of vermiculite and debris travel along the runway the up draft of air carries the smaller fragments of exfoliated vermiculite upwardly into the enlarged chamber and then into the suction air line and deflects the larger fragments of exfoliated vermiculite out of their normal line of travel to separate the debris 70 from the exfoliated vermiculite.

by as the exfoliated fragments of vermiculite and debris travel along the runway the up draft of air carries the smaller fragments of exfoliated vermiculite upwardly into the enlarged chamber and then into the suction air line and deflects the larger fragments of exfoliated vermiculite out of their normal line of travel to separate the debris from the exfoliated vermiculite. 5

2. A machine for separating fragments of exfoliated vermiculite from debris such as stones and unexfoliated fragments of vermiculite, comprising an inclined runway along which the exfoliated vermiculite and debris moves by gravitation, a closed circuit for effecting a flow of air across the said runway comprising blower means 10 and pipe lines connected to the inlet and outlet sides of the blower means, an enlarged chamber connected below the runway to the pressure air line and above the runway to the suction air line for slowing down the velocity of the air forced 15 into the enlarged chamber by the pressure air line, the pressure pipe line being operatively connected with the runway to produce an upward blast of air across the line of travel of said exfoliated vermiculite and debris and the suction 20 air line being positioned above the runway whereby as the exfoliated fragments of vermiculite and debris travel along the runway the up draft of air carries the smaller fragments of exfoliated vermiculite upwardly into the enlarged chamber 25 and then into the suction air line and deflects the larger fragments of exfoliated vermiculite out of their normal line of travel to separate the debris from the exfoliated vermiculite, and a collector connected in the suction air line for separating the smaller fragments of exfoliated vermiculite 30 from the air in the suction line. 35

3. A machine for separating fragments of exfoliated vermiculite from debris such as stones and unexfoliated fragments of vermiculite, comprising an inclined runway along which the exfoliated vermiculite and debris moves by gravitation, a baffle spaced from the end of the runway and positioned in the line of travel of said exfoliated vermiculite and debris, a closed circuit 40 for effecting a flow of air across the said runway comprising blower means and pipe lines connected to the inlet and outlet sides of the blower means, an enlarged chamber connected below the runway to the pressure air line and above the 45 runway to the suction air line for slowing down the velocity of the air forced into the enlarged chamber by the pressure air line, a wire mesh positioned across the said enlarged chamber between the pressure air line inlet and the 50 suction air line outlet for separating the exfoliated vermiculite dust from the larger fragments of exfoliated vermiculite which pass over the said baffle, the pressure pipe line being operatively connected with the runway to produce an upward 55 blast of air across the line of travel of said exfoliated vermiculite and debris and the suction air line being positioned above the runway whereby as the exfoliated fragments of vermiculite and debris travel along the runway the up draft of air carries the smaller fragments of exfoliated vermiculite upwardly into the enlarged chamber and then into the suction air line and deflects the larger fragments of exfoliated vermiculite out of their normal line of travel to separate the debris 60 from the exfoliated vermiculite. 65
